(57) **CLAIM**

We claim the ornamental design for a snow shovel, as shown and described.

DESCRIPTION

FIG. 1 is a front perspective view of the claimed design; FIG. 2 is a bottom, rear perspective view of the claimed design of FIG. 1;

FIG. 3 is a front view of the claimed design of FIG. 1;

FIG. 4 is a rear view of the claimed design of FIG. 1;

FIG. 5 is a left side view of the claimed design of FIG. 1;

FIG. 6 is a bottom view of the claimed design of FIG. 1;

FIG. 7 is a top view of the claimed design of FIG. 1; and,

FIG. 8 is a right side view of the claimed design of FIG. 1.

The broken lines in the drawings illustrate portions of the snow shovel and form no part of the claimed design.
